United States Patent Office

Des. 181,100

Patented Oct. 1, 1957

181,100

TEXTILE FABRIC

Arnold G. Kovler, Fair Lawn, N. J., assignor to Chicopee Mills, Inc., a corporation of New York

Application October 26, 1956, Serial No. 43,541

Term of patent 14 years

(Cl. D92—1)

FIG. 1

FIG. 2

Fig. 1 is a plan view of a textile fabric, showing my new design; and

Fig. 2 is a view of the fabric taken at an angle to the plane of the fabric shown in Fig. 1.

I claim:

The ornamental design for a textile fabric, as shown.
